UNITED STATES PATENT OFFICE

149,892

DESIGN FOR A BROILER

Jacob Meksin, Glendale, Calif.

Application February 17, 1947, Serial No. 136,956

Term of patent 14 years

(Cl. D81—10)

To all whom it may concern:

Be it known that I, Jacob Meksin, a citizen of the United States, residing at Glendale, in the county of Los Angeles and State of California, have invented a new, original, and ornamental Design for Broiler, of which the following is a specification, reference being had to the accompanying drawing, forming part thereof, in which:

Fig. 1 is a top plan view of a broiler, showing my new design;

Fig. 2 is a front view;

Fig. 3 is a rear view;

Fig. 4 is a side view of one side, the two sides being the same in appearance;

Fig. 5 is a bottom plan view; and

Fig. 6 is a top view thereof, with the cover in raised position.

I claim:

The ornamental design for a broiler, as shown.
JACOB MEKSIN.
